UNITED STATES PATENT OFFICE.

DAVID F. SHOPE, OF PORTLAND, OREGON.

BRICKMAKING MACHINE.

Application filed November 18, 1924. Serial No. 750,706.

To all whom it may concern:

Be it known that I, DAVID F. SHOPE, a citizen of the United States, residing at Portland, in the county of Multnomah and the State of Oregon, and having my post-office address at 1396 Wisteria Street, in said city and State, have invented a new and useful Improvement in Brickmaking Machines, of which the following is a specification.

My invention relates to brick making machines and is more particularly adapted for use in the making of the so-called cement bricks, of both the common and the faced types. In the invention herein I have made improvements in the machines now in common use the same being more specifically applied to the end closure. In my invention I have provided an end closure adapted to being held in hinged relationship with a counter balance wherein the end closure is adapted to an end movement as well as to an up and down movement. Further novelty resides in a hinged closure that is adapted to cover the end closure when the same is depressed for its full downward movement, but that is not hinged down if a stop is interposed in the path of the same where a coverage is not necessary; this is essential as a time saver to the workman where the common varieties are being made in the machine. A new and improved locking device is provided for the end closure, to maintain the same in locked position for use.

With these and incidental objects in view the invention consists in certain novel features of construction and combination of parts, the essential elements of which are set forth in the appended claims and a preferred form of embodiment of which is hereinafter shown with reference to the drawing which accompany and form a part of this specification.

In the drawings—

Fig. I is an end elevation of the machine with the end closure in place and in locked position and with the tamping mechanism in raised position.

Fig. II is a front elevation of the machine with the tamping mechanism in lowered position.

Fig. III is a fragmentary sectional view of the machine made to illustrate the construction of the end closure, partially lowered and the supporting mechanism, as well as the hinged closure.

Fig. IV is a sectional view taken on line IV—IV of Fig. I looking in the direction indicated.

Fig. V is a front elevation of the machine showing the end closure in down position and covered with the hinged closure.

Fig. VI is a detached view of the locking device of the end closure.

Like reference characters refer to like parts throughout the several views.

A structural frame 1 having a bed structure 2, and a tamping bar 3 to which the tamping head 4 is attached, forms the main members of the machine.

The end closure 5 is adapted to placement upon the front of the machine and to form the stop for the end of the bricks to be formed. It is desirable that an end movement be imparted to the machine; to accomplish this object the closure has lugs 6 and 7 secured thereto and into which the rod 8 is made secured by screw end, having nuts attached thereto, or by other suitable means. Arms 9 having a counter balance 10 are supported and pivoted about the pin 11. The pin 11 is supported by link 12 which is secured to the cross rod 13 supported within the frame structure of the machine. The arms 9 and 9^a are here shown as two in number and the same are held in alignment and in relation with each other by means of the spreader rod 14. Openings are provided in the arms for a working fit about the rod 8, to permit of the end movement of the end closure in relation with the arms. The closure 5 has a lug 15 upon one end of the same and is held in fixed position upon the closure by rivets 16, or by other suitable fastenings. A tapered pin 17 is secured to the side member of the machine and an opening through the lug permits of the tapered pin passing therethrough to securely position one end of the end closure. A ledge 18 forms a suitable guide and support to maintain the end closure 5 in horizontal alignment. To lock the end closure in position after the same has been positioned the handled member 19 is held in hinged relationship within the lug 20 by means of the pin 21. The pin 21 has a square head 22 adapted to engagement with the spring member 23 that is secured to the end closure by suitable fastenings 24. The spring 23 affords substantial pressure being supplied against the head of the pin and as the handle is rotated about a horizontal pivot the pin 21 is also rotated be-

cause the handle member is secured thereto and in fixed relation therewith. This rotates the head 23 of the pin, and the flat surface of the head tends to position the pin 5 when the same contacts with the spring 23. The spring maintains the handle in and out of engagement.

In certain operations of the machine it is required to lower the end closure only a part 10 of the way down as is shown in Fig. III, while in certain other operations it is required that the same be lowered to the full low position as is shown in the dotted lines of Fig. I. When the end closure is lowered 15 but part way the hinged cover remains in placement, but when the end closure is lowered to the full low position the hinged cover is actuated and covers the end closure to prevent aggregates and other materials 20 from engaging upon the end closure, while in the lowered position. The hinged cover is composed of two parts 27 and 28, the upper, or 27 is secured to the machine frame by suitable fastenings, and the lower or 28 25 is hinged thereto by suitable hinges 29. The lower or 28 is held in a raised position by means of the spring 30. To facilitate the ease of operation and to eliminate the shock due to the lowering of the end closure, I 30 have provided a guideway 32 having a rise 33 in its periphery upon which the follower 31 engages in its travel. The arms 9 being supported about the link 12 permits of the forward movement of the closure plate and 35 the contact of the follower with the rise in the periphery tends to stop the shock incident to the lowering of the same. When it is desired that the end closure be lowered for a part of its total travel a stop 36 is 40 interposed within the path of the arm and arrests the travel of the same. The stop 36 is secured to the frame structure of the machine as shown at 39, and is secured thereto by suitable fastening means as shown at 37. 45 To place the stop in operative position, the stop 36 has a lug 38 that engages the frame structure 39, and maintains the stop 36 in fixed position. When it is desired to lower the end closure for the full downward travel 50 of the same the stop is placed in position as illustrated in Fig. II and in the downward travel of the arms 9 the cross bar engages the trip 35 secured to the lower member 28 and since the same is secured to the lower member 28 the same is caused to rotate about the pins of the hinges 29 and to cover the end closure when the same is de-

pressed to the full downward stroke. In doing so additional tension is placed in the spring 30 and as soon as the end closure is raised by manual or other manipulation the spring returns the lower cover 28 to its raised or normal position.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What I claim is:

1. A new and improved brick making machine, comprising a frame structure, arms held in suspended relationship with the frame and adapted to being lowered, a counter balance and an end closure supported by the arms, and a hinged cover adapted to being actuated when the arms are depressed to the full lowered position.

2. A new and improved brick making machine, comprising a frame structure, arms held in suspended oscillating position with relation to the frame, means adapted to position the arms when lowered partially, counterbalancing means and an end closure secured to the arms, the end closure adapted to an endwise movement in relation to the arms, locking means adapted to position the end closure and maintain the same in locked position, and means adapted to cover the end closure when lowered to an extreme low travel of the same.

3. A new and improved brick making machine, comprising a frame structure, arms adjustably supported within the frame, a counter balance and an end closure adjustably connected to the arms, and means for predetermined the stop position of the arms when lowered.

4. A new and improved brick making machine, comprising a frame of structural material, arms adapted to being raised and lowered, maintained within the frame, counterbalancing means adapted to the arms, an end closure, having a locking means, secured to the arms and adapted to lateral movement in relation therewith, and means adapted to being actuated by the lowering of the arms to cover the end closure when lowered to primary position.

DAVID F. SHOPE.
